UNITED STATES PATENT OFFICE.

CHARLES G. WIELAND, OF HOBOKEN, NEW JERSEY.

STEAM-BOILER.

No. 853,665.

Specification of Letters Patent.

Patented May 14, 1907.

Application filed December 31, 1906. Serial No. 350,231.

To all whom it may concern.

Be it known that I, CHARLES G. WIELAND, a subject of the German Emperor, and a resident of Hoboken, in the county of Hudson and State of New Jersey, have invented certain new and useful Improvements in Steam-Boilers, of which the following is a specification.

It has been a long felt want in the construction of steam-boilers, to limit the amount of water in the boiler for the purpose of producing steam in as short as possible time. In the diverse attempts to design boilers with this end in view, it was found that the supply of feed-water to the boiler became a problem of great importance.

It is now the object of the present invention to produce a boiler simple of construction and of a very small water-space, which space can be regulated according to the requirements, while at the same time devices are connected to the boiler, for automatically supplying feed-water to the same for the purpose of retaining the level of the water in the boiler approximately at a constant height.

The invention is illustrated in the accompanying drawings, in which

Figure 1 is a central vertical cross-section of the boiler with its feeding device, Fig. 2 a perspective view of a part of the feeding device, Fig. 3 a detail view of the automatic valve, operating the feeding device, Fig. 4 a detail view of the pressure regulating valve, and Fig. 5 a modification of a detail of construction.

1 in Fig. 1 is a boiler of the vertical type, walled-in in the inclosure 2, having the usual fire-box 3, with the grate 4 and the-ash-pit 5. For the purpose of increasing the heating 40 surface, flue spaces 6 are provided, connected by means of passages 7 to the chimney.

A bell 8 is centrally located within the boiler, closed at its lower end and open at its upper end. A rod 9, secured thereto, passes through a stuffing box 10, and is provided with a hand-wheel 11 and screw-threads 12, in mesh with corresponding threads of the yoke 13. This bell 8, as will be seen, is adjustable, so that its distance from the bottom of the boiler may be regulated at will, while guides 14, secured to the bell, keep the bell in its central position. A manhole 15 in the bell 8 is provided for the purpose of cleaning the same, when necessary, and this manhole coincides with a similar manhole 16 of the boiler 1.

A feed-water pipe is shown at 17, and leads to the cylindrical receptacle 18, located at a convenient point near the boiler, it is entirely closed and contains a movable cylinder 19, 6s rotatably carried by the top of the casing 18 by means of a shaft 20, to which shaft a turbine-wheel 21 is secured, so that with the rotation of this turbine-wheel 21, the cylinder 19 within the casing 18 is caused to rotate. 65 This casing is furthermore provided with a steam-pipe 22, leading to the steam space of the boiler, having a valve 23, a valve rod 24, which is pivotally connected to the bell-crank 25, carried by a bracket 26, secured to 70 the inner walls of the boiler, while a rod 27 forms a connection to a hollow float 28, normally resting on the surface of the water in the boiler and of annular shape, so that its movement will not be interfered with by the 75 friction along the inner walls of the boiler 1 and the outer walls of the bell 8.

The steam-pipe 22 is provided with a jet 29, directed tangentially against the blades 30 of the turbine-wheel 21, so that steam, 80 passing out through the jet 29, causes the rotation of the cylinder 19. A supply-pipe 31 leads to a suitable reservoir for the feed water.

The cylinder 19 shows a number of peripheral ports, one of which 32 coincides with 85 and is on the same level as the feed-water pipe 17, a second one 33 coincides with the supply-pipe 31, while a third port 34 coincides with the steam pipe 22. 90

The casing 18 has a release-valve 35, connected to a lever 36, pivoted to a lug 37, secured to the top of the casing 18. A finger 38, extending downwardly from the lever 36 is in the path of a cam 39 on the upper rim 95 of the cylinder 19, in such a way that whenever the cam 39 engages the finger 38, the valve 35 is opened, while any excess of the pressure within the cylinder 18 will cause the valve to close again. 100

When the boiler is filled with water to its normal height, the float 28 keeps the valve 23 normally closed, whenever the level of the water should sink below its normal height, the valve 23 is opened and, in the first instance, steam will be emitted from the jet 29 and cause the rotation of the cylinder 19. As soon as port 34 now coincides with the steam-pipe 22, the pressure within the boiler is communicated to the cylinder 19, and the port 32 of this cylinder simultaneously coinciding with the feed-water pipe 17, the water

contained in the cylinder 19 is fed by gravity to the boiler 1. In the further course of the rotation of the cylinder 19, ports 32 and 34 will leave their respective pipes, and the cam 39 causes the opening of the valve 35, so that steam will escape and the space within the cylinder have no more than atmospheric pressure. Since port 33 in the rotation of the cylinder 19 is now coinciding with the supply-pipe 31, feed-water enters the cylinder until in the further rotation of the same the cam 39 leaves the lever 38, and the ports 32 and 34 coincide again, respectively, with the feed-water pipe 17 and the steam-pipe 22. This play is repeated until the level of the water rises to its normal height, when the float is lifted and closes the valve 23.

Fig. 5 illustrates a modification of the inner bell, adapted to determine the water-space in the steam boiler. This bell 40 is provided with an interior bell 42, communicating by means of a pipe 41 through the bottom of the bell 40 with the water space of the boiler. The float 28' in this modification is located within the interior bell 42.

The water space of the boiler may be regulated to any predetermined degree by lifting or lowering the bell 8.

As new and useful is claimed and desired

to be secured by Letters Patent of the United States:—

1. In a steam boiler, the combination with a water-space, of rotatable means capable of interruptedly feeding water to said space, means adapted to operate said water-feeding means, and automatic means for controlling said operating means.

2. The combination with a steam boiler, of a receptacle, a connection between said receptacle and the water-space of said boiler, a connection between said receptacle and the steam-space of said boiler, a valve controlling said steam connection, a float controlling said valve, a cylinder within said receptacle and adapted to be rotated by opening said valve, a supply-pipe connected to said receptacle, ports in said cylinder and adapted to alternately coincide with said water connection, steam connection and supply pipe, and a valve in said receptacle and adapted to be operated by said cylinder.

Signed at New York, in the county of New York and State of New York, this 17th day of December, A. D. 1906.

CHARLES G. WIEI AND.
